UNITED STATES PATENT OFFICE.

J. BENNETT WALLACE, OF CHICAGO, ILLINOIS, ASSIGNOR TO MYERS MANUFACTURING COMPANY, OF SAME PLACE.

VAPOR-BURNER.

SPECIFICATION forming part of Letters Patent No. 314,404, dated March 24, 1885.

Application filed May 8, 1884. (No model.)

To all whom it may concern:

Be it known that I, J. BENNETT WALLACE, of Chicago, in the county of Cook and State of Illinois, have invented certain new and useful Improvements in Hydrocarbon-Vapor-Generating Burners; and I do hereby declare that the following is a full, clear, and exact description thereof, reference being had to the accompanying drawings, and to the letters of reference marked thereon, which form a part of this specification.

This invention relates to hydrocarbon-vapor-generating burners having an induction-pipe, and more particularly to devices in such burners for at times deflecting the current of vapor to the exterior of the burner, whereby the flame of such vapor may keep the generating-passages heated when the burner is not in active use.

20 The invention consists in certain novel features of construction, hereinafter fully set forth, and pointed out in the claims.

In the drawings, Figures 1 to 5, inclusive, show the improvement applied to a burner having its induction-tube inclined with reference to the base of the burner proper. Fig. 1 is a front elevation. Fig. 2 is a section in the plane of line $x-x$ of Fig. 1, showing a side elevation of the induction-tube and needle-valve tube. Fig. 3 is a top or plan view with burner-cap removed, and a principal part of the burner base-plate broken away. Fig. 4 is an indirect section in the line $y-y$ of Fig. 2, but vertical through the ascending liquid-tube of

35 Fig. 1. Fig. 5 is a transverse section of the induction-tube and deflector in the line $z-z$ of Fig. 4. Figs. 6 to 10, inclusive, show the invention applied to a burner having a curved induction-tube. Fig. 6 is a perspective view

40 of such a burner. Fig. 7 is a plan or top view showing the burner-cap removed and a portion of the burner base-plate removed. Fig. 8 is a vertical section in the plane of $x-x$, Fig. 7, showing the induction-tube, the deflector, and the needle-valve tube in side elevation.

45 Fig. 9 is a section in the indirect line $y-y$ of Fig. 8. Fig. 10 is a transverse section of the induction-tube and deflector in the line $z-z$ of Fig. 8. Fig. 10^a shows in end view a modified 50 form of the deflector. Figs. 11 and 12 show the improvement applied to a burner having

a vertical induction-tube. Fig. 11 is a front elevation, and Fig. 12 is a central vertical section.

The same letter is applied to the same part 55 in all figures of the drawings.

The style of burner here shown is that in which a perforated cap is employed in connection with a base-plate which supports the induction-tube. The invention is, however, 60 applicable to burners in which the induction-tube is otherwise upheld.

The invention contemplates the presence of liquid-conveying pipes, or of a body of metal connecting with such pipes in the neighborhood thereof, against which the vapor-flame may be deflected for the purpose of keeping the generating parts hot while the burner is disused.

In the present drawings, A is a burner base-plate. B is a pipe conveying liquid into contact with parts heated by the burner-flame. C is a pipe communicating with the pipe B at its top. D is a lateral branch of the pipe C. D' is a tubular projection of the pipe D, arranged in the prolonged axis of the induction-tube of the burner. E is the shaft or stem of the needle-valve screw-threaded into the projection D'. E' is the point of the needle-valve, seen protruding through the ejection-orifice 80 of the tube D. F is the induction-tube of the burner. G is the deflector, and G' is the handle or lever by which the deflector is moved from one of its positions to the other.

The distinctive feature of my improvement 85 is found in the construction of the induction-tube with a longitudinal slot in one side thereof and a movable part fitted to the slot, which in one position partially forms the wall of the induction-tube, and in another position it partially occupies the passage of said tube, and operates as a deflector by which the vapor and flame are directed upon exterior parts of the burner.

As the best means of securing the desired 95 movement of the deflector, and of giving the proper direction to the vapor when the latter is deflected thereby, said deflector is preferably pivoted (usually at or near its upper end) to the induction-tube or to an adjacent part of 100 the burner.

In the drawings the deflector is shown as

tubular, but it may, if preferred, be parti-
tubular, or trough-shaped, as shown in Fig.
10^a. It is constructed to fill the slot or cut-
away portion of the induction-tube when
5 thrown out of use, and is preferably shaped
in its inner surface to conform to the circular
interior curve of the induction-tube, as indi-
cated in Figs. 5 and 10. Said deflector, as
will be observed, is limited in its movement,
10 so that when its lower or outer end is thrown
inward its mouth or opening will be in posi-
tion opposite the needle-valve opening, and
will thus perfectly intercept the vapor that
would otherwise enter the induction-tube,
15 while the upper or inner end is in position to
direct the vapor or flame against the proper
parts to be heated. The inward-swinging
movement of the deflector may find its natu-
ral and proper limiting-stop in the conforma-
20 tion of the tubes, the free end of the deflector
striking against the opposite wall of the in-
duction-tube. The outer movement may be
arrested by different means or stops in differ-
ent cases.

25 In Figs. 1 to 4, for example, the upper end
of the deflector is provided with a projection,
 g^3 , which strikes an opposing stationary sur-
face when the inner surface of said deflector
comes flush with the inner surface of the in-
30 duction-pipe.

In Figs. 6 to 9 the prolongation of the de-
flector beyond the pivot g serves the same pur-
pose, while in Figs. 11 and 12 the lower or
35 free end of the deflector strikes a neighboring
stationary part. The projection g^3 in Figs. 1
to 4 also serves the purpose of deflecting the
vapor or flame more directly against the parts
through which the vapor or liquid passes to
the needle-valve, and which, as will be seen
40 in all the figures, are generally proximate to
the said deflector.

For the purpose of swinging the deflector
and of retaining it with certainty in either po-
sition given it, different details of construction
45 may likewise be employed.

In Figs. 1 to 4 a horizontal lever, G' , is pivoted
to a stationary arm, g^2 , on the tube C, and
to the deflector G. By reason of the inclina-
tion of the deflector and the induction-tube in
50 said Figs. 1 to 4, and of the incidental friction
of the relatively-movable parts, the deflector
will retain its position at either extremity of
its throw.

In Figs. 6 to 10 the same condition as to the
55 inclination and friction last referred to obtain,
and as a further provision for retaining the

deflector the lever G' (which is in a degree
elastic and is rigidly attached to the deflector)
is arranged to bear upon the transverse or
horizontal branch tube D.

In Figs. 11 and 12 the deflector is provided
with a downward projection, G^2 , which bears
closely against a longitudinal lateral rib, d , on
the side of the tube D, with sufficient friction
to hold the deflector in its advanced position.

The deflector is used not only to deflect the
vapor and give a flame beneath the burner,
but also to deflect the stream of liquid for in-
itially heating the burner, when this method
of such heating is employed. The drip-cup H
may be accordingly arranged in position to
catch the liquid that will fall from the parts
upon which it is directed, as shown in Figs.
11 and 12.

It is to be understood that I do not broadly
claim devices whereby the vapor may be di-
rected either within the burner or toward ex-
terior parts of the burner, as such devices in
various forms are well known.

I claim as my invention—

1. The combination, with a longitudinally-
slotted induction-tube, adjacent parts to be
heated, and a valve for the ejection of vapor,
of a deflector movably mounted in the slot of
the induction-tube, substantially as described.

2. The combination, with a longitudinally-
slotted induction-tube, a valve for the emis-
sion of vapor, and vapor-generating parts, of
a movable deflector fitted to the slot of the in-
duction-tube, and having its inner surface
shaped to conform to the stationary wall of the
said tube, substantially as described.

3. The combination, with a longitudinally-
slotted induction-tube, a valve for ejection of
vapor, and vapor-generating parts, of a de-
flector fitted to the slot of the induction-tube,
and pivoted at its end adjacent to the burner,
and a lever attached to the deflector, substan-
tially as described.

4. The combination, with a longitudinally-
slotted induction-tube of a vapor-generating
burner, of a pivoted deflector fitted to the slot,
and a stop constructed to arrest the deflector
in position to form a part of the wall of the
induction-tube, substantially as described.

In testimony that I claim the foregoing as
my invention I affix my signature in presence
of two witnesses.

J. BENNETT WALLACE.
